UNITED STATES PATENT OFFICE.

WILLIAM E. DUNNING AND JACOB BACHOFEN, OF ALLIANCE, OHIO, ASSIGNEES TO THE MCCASKEY REGISTER COMPANY, OF ALLIANCE, OHIO, A CORPORATION OF OHIO.

FILING APPLIANCE.

Application filed July 16, 1923. Serial No. 651,815.

To all whom it may concern:

Be it known that we, WILLIAM E. DUNNING and JACOB BACHOFEN, citizens of the United States, residing at Alliance, in the 5 county of Stark and State of Ohio, have invented certain new and useful Improvements in Filing Appliances, of which the following is a specification.

The invention relates to a filing appliance 10 for sales bills and other similar papers, in which a series of hinged holder frames or leaves may be operatively mounted upon a supporting elevator frame carried in a fire-proof case having a rectangular box base 15 into which the frame and superposed holders may be lowered and a lid for enclosing the same when not in use.

In filling appliances of this kind various methods have been employed for mounting 20 and operating the hinged holders upon or in a supporting base or frame, and in some instances two different methods have been employed for operating adjoining or adjacent series of holders; but in all such 25 modes of operation, there are certain structural conditions which practically limit the number of hinged holders which can be successfully manipulated by one mode of operation.

30 A principal object of the present improvement is to combine and coordinate three several methods of mounting and operating as many series of hinged holders continuously connected together, so as to increase to a maximum the bill holding capacity of the combined series in a single and continuously operative bank of holders.

In the preferred normal position of such a bank or series of hinged bill holders, the 40 same are by preference normally mounted and maintained in upright or vertical position when not in use, and a further object of the improvement is to operatively mount the bank of holders upon an elevator supporting frame carried in the box body of the case, in such a manner that the bank of holders may be raised and operatively supported at the open top of the case and can also be lowered and enclosed in the case, 45 and in normal upright position.

A preferred form of the improvement is illustrated in the accompanying drawings, in which—

50 Figure 1 is an elevation section of the case with the lid closed, showing in side

elevation the filing appliance lowered and enclosed therein;

Fig. 2, a detached face view of one of the bill holders;

Fig. 3, an elevation section of the case 60 with the lid raised, showing in side elevation the filing appliance elevated through the open top of the case;

Fig. 4, a similar view showing the bank 65 of holders moved rearward into the operative position;

Fig. 5, a fragmentary view of the same showing the table leaf swung forward toward prone position;

Fig. 6, a similar view showing the table 70 leaf swung forward and downward into prone position;

Fig. 7, a similar view showing the first 75 three holders of the forward section of the series, swung forward toward prone position;

Fig. 8, a similar view showing the first 80 six holders comprising the forward section, swung downward into prone position;

Fig. 9, a similar view showing the first 85 four holders of the intermediate section, swung forward toward prone position;

Fig. 10, a similar view showing all of the eight holders comprising the intermediate section, swung downward into prone position upon the forward section;

Fig. 11, a similar view showing the first 90 four holders of the rear section, swung forward toward prone position;

Fig. 12, a similar view showing all but 95 one of the nine holders comprising the rear section, swung forward into prone position upon the forward and the intermediate sections;

Fig. 13, a similar view showing all the 95 holders of the forward section and four holders of the intermediate section, together 100 swung forward toward prone position;

Fig. 14, a similar view showing all the 100 holders of the forward and intermediate sections and three holders of the rearward section, together swinging forward toward prone position;

Fig. 15, an elevation section of the case 105 with the lid opened, showing in side elevation the holder supporting frame elevated therein with the bank of holders removed therefrom;

Fig. 16, a detached perspective view of the elevator supporting frame;

Fig. 17, a detached perspective view of the elevator guide ways;

Fig. 18, a detached perspective view of the bill holder carriage frame;

5 Fig. 19, a fragmentary view of one bearing and latch for the fulcrum pivots;

Fig. 20, a fragmentary perspective view of the elevator releasing lever;

10 Fig. 21, a detached front face view of the table leaf;

Fig. 22, an edge view of the same; and

Fig. 23, an enlarged fragmentary side elevation showing the hinge connection and the yielding track support for the table leaf.

15 Similar numerals refer to similar parts throughout the drawings.

The case for the filing appliance may comprise a box body 22 open at the top, a lid 23 hinged at 24 to the rear rim of the body and provided with a combination lock 25 and a handle bar 26 along the forward edge, by means of which handle the lid may be readily raised and lowered.

20 The elevator supporting frame 27 is provided with a plurality of guide rollers 28 extending laterally from each side, which are adapted to operate in guide ways 29 and 29' provided therefor on the inner side of the side walls of the body of the case; 30 two guide rolls spaced one above the other being preferably provided near the rear end of the elevator frame, and a third side roll being preferably spaced a substantial distance forward therefrom, so as to give 35 triangular points of support for holding the elevator frame from tilting.

Supporting links 30 are provided on each 40 side of the elevator frame, the upper ends of which are preferably connected with brackets as 31 secured to the underside of the lid, and the lower ends of which are provided with elongated slots 32 in which are slidably engaged supporting pins 33 extending laterally from the sides of the elevator frame. The lower ends of these slots

45 form bearings for the pins for raising and carrying the elevator frame when the lid is opened to the upright position shown in Figs. 3 to 15, and the pins may slide in the slots to permit the links to move downward when the lid is finally closed after the elevator carriage rests upon the bottom of the case, as shown in Fig. 1.

The weight of the lid, the elevator carriage and the bank of holders superposed thereon, is preferably sustained or counterbalanced at least in part, by a pair of coiled compression springs 34 in each side of the case; the springs being located around telescoping tubes 35 and rods 36. The lower ends of the telescoping tubes are secured to a cross head 37 pivotally connected to a bearing bracket 38 in the forward corner of the bottom of the case; and the upper ends of the telescoping rods are secured to

a cross head 39 pivotally connected to a bearing bracket 40 on the under side of the lid; from which upper cross head 39 may depend a shield 41 extending around the outer sides of the springs and rods, and having a band 42 on its lower end extending around the inner side thereof, all in well known manner.

5 Lid supporting links 43 are provided in the sides of the case, and the same may have 75 their upper ends pivotally connected to the bearing brackets 40 on the under side of the lid. These links are provided with longitudinal slots 44 throughout the greater portion of their length, which slidably engage supporting posts 45 extending inward from the sides of the body of the case. The slots 44 are curved abruptly forward at their lower ends so as to form shoulders 46, adapted to rest and bear upon the supporting posts 45 when the lid is fully opened into upright position, as shown in Figs. 3, 4, and 13; in which position the lid may lean slightly rearward, as illustrated in the drawings.

90 The lid supporting links normally swing rearward by gravity, so that their shoulders 46 will bear upon the supporting pins 45, and when it is desired to lower the lid, both links may be swung forward in unison to disengage the shoulder from the pins, by means of a releasing lever 47 secured to the end of a rock shaft 48 extending transversely through the supporting frame and having a crank arm 49 on each end with a crank pin 50 thereon extending inward in rear of the lower end of the corresponding link, so that a forward movement of the releasing lever moves the lower ends of the links forward, thereby disengaging the 95 bearing shoulders from the supporting pins and permitting the pins to slide in the slots as the links move downward with the lid.

100 The releasing lever 47 may be normally held rearward by a coiled expansion spring 51 connecting it with the elevator frame, and it is preferred to provide a stop finger 52 extending inward in the path of a stop finger 53 extending inward and downward from one side of the bill holder carriage frame 54; so that the releasing lever is positively stopped from operation when the bank of bill holders is pushed rearward upon the carriage into operative position, 105 as presently to be described.

110 The carriage frame 54 is provided with traction wheels 55 which bear and travel upon horizontal track ledges 56 provided in each side of the horizontal frame underneath guide bars 57 overhanging the wheels and forming guide ways in which the wheels operate forward and rearward.

115 The rearward movement of the carriage frame 54 is limited and stopped by the up-

- right back flange 58 extending across the rear end and the frame, and the carriage is automatically locked in this position by a spring latch 59 having a beveled faced hook 60 for springing downward to pass under the forward end of the frame, and then spring upward to engage the same when moved to its rearmost position, as shown in Figs. 4 to 14, inclusive.

At the forward end of its movement, the forward traction wheels ride upward upon the inclined rear end of the blocks 61 on the forward end of the track ledges 56, in the forward ends of which blocks are provided semi-circular recesses 62 for receiving the wheels and holding them against movement in either direction, unless the frame is lifted upward so as to release the wheels from the recesses.

The filing appliance per se may include a bank or continuous series of bill holder frames or leaves 63, 63' and 63'', which are all hinged together at their lower ends by means of interengaging hinge ears 64 and pintles 65, so that their upper ends may swing freely to and from each other; and in front of the foremost holder 63 may be provided a table leaf 66, which is likewise hinged to the lower end of the foremost holder so that it may swing freely to and from the upper end of the same.

All the bill holders are made exactly alike, with recesses 67 and spring clips 68 in each face for receiving and clamping sales bills or the like in well known manner; but for operating purposes, according to the present improvement, they may be described as comprising three several sections or series, which may include some six holders 63 in the forward section, some eight holders 63' in the intermediate section, and some nine holders 63'' in the rearward section.

Three points of support are provided for the bank of holders when in normal upright position, the first being a pair of spring sustained tracks 69 extending rearward from a hinge connection with the forward corners of the elevator frame, for supporting the hinged end of the table leaf; the second being a pair of bearings 70 on the forward end of the carriage 54, for supporting the pintles 65 of the hinges between the contiguous holders of the forward and intermediate sections; and the third being a pair of abutment rollers 71 mounted on the inner side of a swinging frame 72 carried upon parallel links 73 rising from the sides of the carriage frame 54 and controlled by the movements of the rearmost holder of the intermediate section, which rollers form abutments for the side edges of the rearmost holder of the rearward section, as best shown in Figs. 4 and 12.

The forward ends of the tracks 69 are hinged at 74 to the forward end of the elevator frame, in rear of which each track is supported by compression springs 75 bearing upon guide lugs 76 through which operates guide rods 77 surrounded by springs. The rods are provided with heads 78 bearing upon the upper end of the springs and pivotally connected with the tracks 69, so as to yieldingly sustain the same, as well shown in Fig. 16. Upon the outer side of each yielding track is formed or secured an auxiliary track 79 which is inclined upward and forward from the plane of the main track 69, from a point at or near the middle to the forward end thereof.

A shaft 80 is journaled in bearings 81 at the forward edge corners of the table leaf 66, upon the ends of which shafts are provided traction rollers 82 extending beyond the side edges of the leaf and adapted to ride upon the auxiliary tracks 79 when the leaf is standing in normal upright position, as shown in Figs. 3, 4 and 22; in which position of the parts, the bearings 81 are near above the main tracks 69 so as to bear and ride upon the same when the table leaf is swung forward, as shown in Fig. 23.

Another shaft 83 is journaled in the lower end of the table leaf at an interval above the shaft 81 and also above the position of the pintles 65'' upon which the leaf is hinged by ears 64'' on its rear side, as shown in Fig. 23; upon the ends of which shaft 83 are provided traction wheels 84, which are partially located in a recess 84' so that the wheels will protrude therefrom for riding upon the main tracks when the table leaf is swung forward and downward into prone position, as shown in Fig. 23.

In this position of the parts the side edges of the table leaf rest and ride upon the forward ends of the main tracks, and the foremost holder 63 of the bank of leaves is supported by the traction wheels 84 and the bearings 81 resting upon the main tracks 69, which in turn are thrust upward and sustained by the compression springs 75, as well shown in Fig. 23. The location of the forward pintle 65'' between the wheels 84 and the bearings 81 serves to hold the table leaf in prone position.

These parts have been described in the positions occupied by them when the bank of leaves is pushed rearward upon the carriage frame into operative position, as shown in Figs. 4 to 14 inclusive. When, however, the bank of leaves is moved forward with the carriage frame, as for lowering the case, the holders and the table leaf being in normal upright position; the traction rollers 82 at the lower corners of the table leaf, ride upon the auxiliary tracks 79, which carry the rollers upward from the plane of the main tracks, so as to sustain the table leaf and the holders of the forward

section in upright position, as shown in Fig. 3; the main tracks not being free to rise far enough for that purpose, because of the contact of their rear ends with the lower ends 5 of the bill holders.

The pintles 65' of the hinges between the contiguous holders of the forward and intermediate sections, are preferably retained in the bearings 70 on the forward end of 10 the carriage frame, by means of gravity latches 85, as shown in Fig. 19; and for the purpose of coordinating the movements of the intermediate sections of holders, the eighth or rearmost series of the intermediate 15 section is provided with guide rollers 86 on the lower corners, which rollers extend laterally for operating in guide ways 87 carried by the swinging frame 72, so that the frame will conform to the forward and rearward movements of the hinged end of the 20 holder which carries the guide rollers.

When the filing appliance is not in use, it is lowered and enclosed in the fireproof case, as shown in Fig. 1, and when it is desired to 25 use the same, it is elevated by the upward thrust of the compression springs 34, supplemented or at least controlled by grasping the handle bar on the forward end of the lid. The lid rises alone until the supporting pins 33 bear upon the lower ends of the 30 slots in the supporting links 30, whereupon the elevator carriage and bank of the leaves thereon are raised to the top of the case, and there locked by the lid supporting links 43, as shown in Fig. 3.

The forward end of the bank of holders is then lifted so that the forward traction wheels 55 may ride out of the retaining recesses 62 in the blocks 61, and the bank of 40 leaves is pushed rearward upon the carriage frame into operative position, as shown in Fig. 4, wherein it is locked by the engagement of the hook of the spring latch 59 against the forward edge of the carriage 45 frame. The table leaf 66 may then be swung forward from the normal position shown in Fig. 23, to the position shown in Fig. 5, and thence downward to the prone 50 position shown in Figs. 6 and 23. An index may be provided on the inner upper side of the table leaf or upon the forward 55 face of the foremost holder as may be desired, and when the table leaf is swung forward and downward into prone position, the series of holders is ready for use.

The operation of the section comprising the first six holders is accomplished in the manner shown in Figs. 7 and 8, by swinging the upper ends of the desired number of 60 holders forward and downward, which carries the hinged ends thereof downward and rearward under the foremost upright holder of the intermediate sections, the same being permitted by a depression of the rear ends 65 of the yielding tracks 69 upon which the

hinged end of the table leaf moves rearward while supporting in upright position the holders of the forward section which have not been swung forward. This movement of the holders in the forward section may 70 be termed an under swinging operation, and during this movement, the forward end of the table leaf bears and slides upon the forward ends of the tracks.

The same pintle 65' which serves as the 75 support for the rear holder of the forward series, serves also as the fulcrum support for the forward holder of the intermediate and rearward sections during the operation thereof.

The operation of the holders of the intermediate section is accomplished as shown in Figs. 9 and 10, and as one or more holders of this section are swung forward upon the fulcrum pintle 65', the guide rollers 86 on 80 the lower corners of the rearmost holder of the section operate in the guide ways 87 to swing the frame 72 and the abutment roller thereon forward; thereby sustaining all the holders which have not been swung forward 90 in upright position, as they are moved upward by the forward swinging of the forward holders in well known manner, until all the holders of the intermediate section have been swung forward and downward to 95 prone position upon the forward section, as shown in Fig. 10.

The operation of the intermediate section of the holders is thus accomplished by what is commonly known as the gravity method, 100 for the reason that the holders are swung and held in prone position, as well as in upright position, by the weight of the upright holders, without the use of springs or counterweights, and that the same weight tends 105 to swing the holders into either one or the other position, when they are manually moved more than half way toward the same.

The operation of the intermediate section of holders is also accompanied by what may 110 be termed a moving abutment, for the reason that the operation of the holders of the intermediate section moves the swinging frame which carries the abutment rollers and also the rearward section of holders, 115 to and fro, so that they constitute a moving abutment for the rearmost holder of the intermediate series. The movements of the holders of the intermediate section may thus be referred to as a moving abutment gravity 120 operation.

The operation of the rearmost section of holders is also accomplished by the gravity method, for the reason that when all the 125 holders of the intermediate section have been swung forward into prone position, the hinge connection between the rearmost intermediate holder and the foremost holder of the rearward section constitutes a fixed fulcrum upon which the holders of the rear- 130

most sections are operated by the gravity method. As there is no further forward movement of the swinging frame and the abutment rolls, the same constitute what 5 may be termed a stationary abutment for the rearmost holder of the rearward section; which holder moves upward and downward at various degrees of inclination, as the several holders in front of it are swung 10 from normal upright to prone position and vice versa, as shown in Figs. 11 and 12. The movements of the holders of the rearward section may thus be referred to as a stationary abutment gravity operation.

15 Although, for convenience, the movements of the holders in each of the several sections has been described as an independent or separate operation, it will be understood that the operation of each and all the sections 20 may be and in practice are usually coordinated. For instance, when all the holders are in normal upright position, as shown in Fig. 6, and it is desired to have access to one of the holders of the intermediate 25 section, it is only necessary for the operator to grasp the free end of the holder to which access is desired, and by pulling the same forward and downward, all the holders in front of it, including those of the intermediate 30 section and all of the forward section, will operate as a unit by turning on the fulcrum formed by the bearings 70 on the forward edge of the carriage frame, as shown in Fig. 13.

35 It will also be understood that when the same number of forward holders have been swung forward into prone position, they may be all together swung upward as a unit into normal upright position, by merely lifting the forward free end of the foremost 40 holder; and it will also be understood that it is not necessary to swing the table leaf forward into prone position, as shown in Fig. 6, before the holders proper are operated, for the reason that the table leaf 45 may be swung to and fro in conjunction with the foremost holder, if it is desired to do so.

50 And finally, when all of the holders are in normal upright position, as shown in Fig. 6, and it is desired to have access to one of the holders in the rearward section it is only necessary to grasp the upper free end of the holder to which access is desired, 55 and by pulling the same forward and downward, all the holders in front thereof in the several sections will be operated, as a unit, each according to their own law, as shown in Fig. 14; in short, all of the holders may 60 be operated as a unit to and from a prone position, by a coordination of the operation of the holders in all of the several sections.

In this manner there may be combined in a unitary filing appliance, a continuous series of hinged holders including three 65 several sets, the holders in each set operating according to a different mode or method and also in coordination with the operation of the holders in each of the other sets; and each set may contain as many holders as 70 may be conveniently and practically operated together by its particular mode of operation, thereby increasing to a maximum the number of holders which can be combined in a single unitary filing appliance. 75

When the filing appliance is not in use, and it is desired to lower the bank of bill holders into the well formed by the box body of the case, for fire or burglar protection, the holders and the table leaf are all swung 80 into normal upright position, as shown in Fig. 4; after which the spring latch 59 is disengaged from the forward edge of the carriage frame, and the same with the bank 85 of holders thereon are moved forward until the forward set of traction wheels 55 ride upon and enter the recesses in the block 61, during which movement the traction rolls 82 on the lower corners of the table leaf, 90 ride upon the auxiliary tracks 79 so as to hold the table leaf and the leaves of the forward section in normal upright position, as shown in Fig. 3.

It will be understood that the rearward 95 or operating position of the bank of holders as shown in Fig. 4 is necessary or desirable to prevent the table leaf and the holders superposed thereon from overhanging the forward end of the elevator supporting frame too far for proper support; and that 100 the forward shifting or movement of the same, shown in Fig. 3, is desirable or necessary to prevent the lid from striking the upper ends of the rearmost holders before they are lowered far enough into the case 105 to avoid the same, when the parts are made and arranged in the most desirable proportions for convenient use.

After moving the bank of holders forward, into the position shown in Fig. 3, the releasing lever 47 may be swung forward to disengage the lid supporting links 43 from the supporting pins 45, whereupon the 110 weight of the elevator frame and the bank of leaves thereon, assisted if need be by a forward pull upon the lid handle 26, serves to overcome the action of the counterbalance springs 34, and the carriage with the holders thereon is lowered into the box body 115 of the case, being guided therein by the movement of the guide rolls 28 in the guide ways 29 and 29'.

The downward movement continues until the elevator frame rests upon the bottom of the case, after which the lid is finally closed 120 by the sliding of the supporting pins 33 in the slots of the supporting links 30; which final closing movement of the lid is against

the full force of the compression springs 34, and compresses the same so that their energy is useful in the initial movement of raising the lid when the same is again opened for 5 elevating the bank of holders into position for use.

The improvement in filing appliance cases illustrated and described but not claimed herein is made the subject matter of a companion application for Letters Patent filed 10 herewith, Serial No. 651,814.

We claim:—

1. A filing appliance including a series of normally upright holders hinged together at 15 their lower ends for swinging apart at their upper ends, and supporting means for the series of holders including yielding tracks at one end, movable abutments at the other end and intermediate pivotal bearings arranged for an underswinging operation of 20 one end section thereof, a movable-abutment gravity operation of an intermediate section thereof, and a stationary-abutment gravity operation of the other end section thereof.

2. A filing appliance including a continuous series of normally upright holders hinged together at their lower ends for swinging apart at their upper ends, yielding tracks for supporting the holders in one forward end section of the series, bearings for 25 the hinges of the contiguous holders of the forward end section and an intermediate section of the series, a movable abutment frame for the rearmost holder of the other 30 end section of the series, and means on the hinged end of the rearmost holder of the intermediate series for moving the abutment frame therewith, whereby the forward section of holders can be operated by an underswinging movement, the intermediate 35 section by a movable-abutment gravity oper-

ation, and the rearward section by a stationary-abutment gravity operation.

3. A filing appliance including a continuous series of holders hinged together at their lower ends for swinging apart at their upper ends, and a support for the series carrying yielding tracks at one end for the holders in one end section of the series, bearings intermediate the ends of the support for the 45 hinged ends of the contiguous holders between the one end section and the intermediate section of the series, an abutment for the holders in the intermediate and the other end section of the series, and means on the 50 hinged end of the rearmost holder of the intermediate section for moving the abutment during the operation of the holders of the intermediate section of the series.

4. A filing appliance including a supporting frame, a carriage movable forward and rearward upon the frame having bearings on its forward edge, a series of normally upright holders operatively mounted on the carriage having their lower ends hinged together for swinging apart at their upper ends, the hinged end of an intermediate holder being supported by the bearings, yielding tracks pivoted at their forward ends to the supporting frame and extending rearward under the hinged holders for normally supporting the foremost holder, auxiliary tracks on the sides of the yielding tracks inclined upward and forward from the plane thereof, and traction rollers on the 55 hinged end of the foremost holder for riding on the auxiliary tracks when the carriage and holders are moved forward on the 60 supporting frame.

WILLIAM E. DUNNING.
JACOB BACHOFEN.
